[57] CLAIM

The ornamental design for a water hammock, as shown and described.

DESCRIPTION

FIG. 1 is a perspective view of a water hammock which illustrates my new design:

1 Claim, 6 Drawing Sheets

FIG. 2 is a right side elevational view thereof, the left side elevational view being a mirror image thereof;

FIG. 3 is a top plan view thereof, the bottom plan view being a mirror image thereof;

FIG. 4 is a front elevational view thereof, the rear elevational view being a mirror image thereof;

FIG. 5 is a perspective view of a water hammock which illustrates a first alternative embodiment of my new design;

FIG. 6 is a right side elevational view thereof, the left side elevational view being a mirror image thereof;

FIG. 7 is a top plan view thereof, the bottom plan view being a mirror image thereof;

FIG. 8 is a front elevational view thereof, the rear elevational view being a mirror image thereof;

FIG. 9 is a perspective view of a water hammock which illustrates a second alternative embodiment of my new design;

FIG. 10 is a right side elevational view thereof, the left side elevational view being a mirror image thereof;

FIG. 11 is a top plan view thereof, the bottom plan view being a mirror image thereof; and,

FIG. 12 is a front elevational view thereof, the rear elevational view being a mirror image thereof.

FIG. 1

FIG. 2
